UNITED STATES PATENT OFFICE.

GEORGE C. BIRNEY, OF CHESTER, PENNSYLVANIA.

HOUSEHOLD-BOILER CONNECTION.

Application filed December 11, 1922. Serial No. 606,101.

To all whom it may concern:

Be it known that I, GEORGE C. BIRNEY, a citizen of the United States, residing at Chester, in the county of Delaware and 5 State of Pennsylvania, have invented new and useful Improvements in a Household-Boiler Connection, of which the following is a specification.

My invention relates to new and useful 10 improvements in a household boiler connection, and has for its primary object to provide a single connection or fitting from which a number of circulating pipes, a discharge pipe and a supply pipe are connected 15 with the boiler making it unnecessary to provide the usual two or more openings in the boiler.

In the usual construction of boilers of 20 this character one opening is provided for the discharge pipe, another for the supply pipe and oftentimes a third one for the return pipe or the water circulation which naturally weakens the hot water boiler and adds considerable expense to its manufacture.

25 These disadvantages are entirely overcome by my invention as it is only necessary to provide one opening at the top of the boiler in addition to the one at the bottom for the water circulation there is only one other 30 opening necessary by which my fitting is secured to the boiler for connection with a plurality of pipes. With these ends in view, this invention consists in the details of construction and combination of elements hereinafter set forth and then specifically 35 designated by the claims.

In order that those skilled in the art to 40 which this invention appertains, may understand how to make and use the same, I will describe its construction in detail, referring by numerals to the accompanying drawings forming a part of this application, in which:—

Fig. 1, is a side elevation of a hot water 45 boiler and three heating devices connected therewith by my improved boiler connection.

Fig. 2, is a plan view thereof.

Fig. 3, is a longitudinal sectional view of 50 the fitting or connection showing the manner of connecting certain of the pipes thereto.

Fig. 4, is a side elevation thereof.

Fig. 5, is a plan view of Fig. 4.

In carrying out my invention as here embodied, 2 represents a hot water boiler of any 55 well known or desirable construction, 3 a heating device here shown conventionally as

a hot air heater, 4 is a conventional showing of a gas heater and 5 is a similar showing of a stove or laundry heater. It is to be understood that any other form of heating 60 device may be substituted for any one of those shown and each includes a well known water heating element, such as a coil or water back.

At or near the bottom of the hot water 65 boiler is located a fitting 6 with which are connected the lead-in pipes 7, 8 and 9 leading to each of the heating devices 3, 4 and 5 respectively and if found desirable to this fitting may also be connected a drain cock 10. 70

To the top of the hot water boiler 2 is attached my improved boiler connection or fitting 11 by means of the stem 12 which has a passageway 13 therethrough to form a 75 communication between the hot water boiler and the interior of the connection or fitting. Passing through the stem 12 is a distributing pipe 14 the lower end of which terminates in close proximity to the bottom of the hot water boiler when the device is in 80 place while the upper end of said pipe is threaded into the internally threaded stem 15 the passageway 16 of which is of smaller diameter than the passageway 13 in the stem 12 so that a space of considerable capacity 85 remains between the walls of the stem 12 and the pipe 14.

The boiler connection or fitting is provided with a number of other stems preferably four in number and designated by the 90 numerals 17, 18, 19 and 20. With one of these stems, as 17, is connected a return pipe 21 from one of the heating devices, as 2, while a return pipe 22 leads from another of the heating devices, as 4, to another of the 95 fitting stems as 18 and a third return pipe 23 is connected with the other heating device, as 5, and with another of the stems of the fitting, as 19.

The cold water supply pipe 24 is connected with the stem 15 so as to communicate with the pipe 14 but not with the interior of the fitting 11 and a discharge pipe 25 is connected with another of the fitting stems, as 20 leading to the fixtures, such as faucets, 105 which control the discharge of the hot water from the hot water boiler.

The different pipes may be connected with the boiler connection or fitting in any suitable or well known manner but what seems 110 to be the most practical way is to externally thread each of the stems of the fitting where-

by a union nut 26 may be screwed thereon in a manner similar to that shown in Fig. 3, said nuts engaging the flanges or collars of the pipes to hold them in place.

5 The operation is substantially as follows:—On lighting any one or all of the heating devices the temperature of the water within their heating elements will be raised and set up a circulation through their return 10 pipes to the boiler connection or fitting 11 and then through the passageway 13 in the stem 12 into the upper portion of the boiler while at the same time the colder water at the bottom of the boiler will pass through 15 the fitting 6 to the return pipes and then into the heating elements of the heating devices. Whenever any water is drawn from the boiler it will pass through the passageway 13 in the stem 12 to the interior of the fitting 20 and then through the discharge pipe 25 and as this water is drawn off an equal amount will enter through the supply pipe 24 and the distributing pipe 14 with which it communicates, being discharged at or near 25 the bottom of the hot water boiler.

When only one or two heating devices are connected with the hot water boiler the stems of the boiler connection fitting not in use are closed by suitable caps and likewise the 30 unused stems of the fitting 6 may be closed or a fitting having a less number of stems may be substituted for the fitting 6 shown and above described, such fittings as these being in common every day use. To prevent 35 syphoning a vent 27 is formed in the pipe 14.

Of course I do not wish to be limited to the exact details of construction as herein shown as these may be varied within the 40 limits of the appended claims without departing from the spirit of my invention.

Having thus fully described my invention, what I claim as new and useful is:—

1. The combination with a hot water boiler 45 and a plurality of heating devices of means

for connecting a lead-in pipe with each of the heating devices, a boiler connection secured to the top of the boiler one stem of said connection opening into the boiler, a distributing pipe of smaller diameter than 50 the interior of the stem connected with the boiler passing through said stem and connected with a stem directly opposite the first named stem, said pipe leading to a point adjacent the bottom of the boiler, a supply pipe 55 connected to the same stem as the distributing pipe, a return pipe leading from each of the heating devices and each connected with a separate stem on the boiler connection, and a discharge pipe connected to another stem of the boiler connection.

2. The combination with a water heating system including an upright boiler, a plurality of heating devices, lead-in pipes connected to the lower end of the boiler and each 60 connected with a separate heating device and a return pipe also connected with each heating device, of a boiler connection having a plurality of stems and mounted on the upper end of said boiler by means of one of said 65 stems, a distributing pipe attached at its upper end to a stem directly opposite the one by which the boiler connection is attached to the boiler and projecting through said 70 boiler attaching stem and terminating adjacent the lower end of the boiler, said distributing pipe having a diameter appreciably less than that of the boiler attaching stem to produce a passageway about said 75 distributing pipe directly communicating 80 with the upper portion of the boiler, a cold water supply pipe connected with the same stem through which the distributing pipe is attached, a discharge pipe attached to another of the stems, and means for attaching 85 the return pipes to the other stems of the boiler connection.

In testimony whereof, I have hereunto affixed my signature.

GEORGE C. BIRNEY.
